John Rohdick
by C.P. Soepel,
ATTORNEY

UNITED STATES PATENT OFFICE.

JOHN ROHDIEK, OF NEW YORK, N. Y.

SCOOTER.

Application filed November 8, 1924. Serial No. 748,509.

To all whom it may concern:

Be it known that I, JOHN ROHDIEK, a citizen of the United States, and a resident of the borough of Manhattan, city, county, and State of New York, have invented certain new and useful Improvements in Scooters, of which the following is a specification.

This invention relates to scooters and more particularly to scooters and the like used as toys or play things in which the cars are propelled by the action of the foot upon the platform.

Heretofore, in such scooters, the platform was stationary and was supported on a frame, to which frame, the wheels and also the propelling mechanism was suitably secured, so that the users could utilize one foot upon the platform and the other foot upon the pedal of the propelling mechanism.

The invention consists in providing a movable platform, which, when moved, will operate the propelling mechanism and by the use of this invention, the user may stand either one foot or both feet upon the platform. The invention further comprises the combination of parts whereby a very pleasing, yieldable and resilient operation is obtained.

The invention will be more fully herein-after described and an embodiment thereof shown in the drawings and the same finally claimed in the appended claims.

In the accompanying drawings, Figure 1 is a side view, showing an embodiment of my invention, arranged in the scooter or the like, Figure 2 is a plan view thereof, and Figure 3 is a fragmentary detail view of a driving clutch mechanism, and in which similar reference characters designate corresponding parts through the several views.

Referring to the drawings, and more particularly to Figure 1, the well known wheels 10 are held in position by the frame 11, arranged in two parts, the forward part having a handle 12 and the rearward part preferably having a seat support 13. The frame 11 has between its two parts, the supporting means for a platform, consisting of transverse shafts 14 passing through downwardly extending lugs 15, secured to the lower surface of the platform 16. Around the shafts 14, preferably oppositely wound springs 17 and 18 are arranged and these springs are disposed so as to match with

each other, but in opposite arrangement to each other. One end 19 of each spring presses against the lower surface of the platform 16 and the other end 20 of each spring presses against the frame 11. In the embodiment shown, the end 20 (see Figure 1) is so bent as to pass from the inner part of the frame 11 to the outer part thereof and the body portion of the end 20 of the spring thereby acts to be attached to the frame 11. Normally the springs 17 and 18 have a tendency to press outwardly and thereby maintain the platform 16 disposed at a suitable distance away from the frame 11; and normally the action of this pressure of the springs is substantially equal so that the platform 16 is held in substantially horizontal position. In order to limit the upward movement of the platform 16 away from the frame 11, a buckle joint is provided which consists of two links 21 and 22. The link 21 is pivotally connected with the frame 11, and the link 22 is pivotally connected with the lower part of the platform 16 and these links 21 and 22 are pivotally connected with each other at their free ends by means of a pin 23. Such a buckle joint is provided at each end of the platform 16. One of the links either 21 or 22 is provided with a pin 24 to act upon the other link, so that the action of these links and this pin 24 is such as to limit the extending movement of this buckle joint.

Thus, while the springs have the tendency to move the platform upwardly at either side of the central portion of the platform, the buckle joints have the effect of limiting the movement of this upward movement of the platform.

To one end of the platform 16 is secured a rod 25 to which the segment of a gear or a rack 26 is secured. The teeth of this gear or rack mesh with the gear 27 on the rear axle 28. The gear 27 is connected with a coaster mechanism as is well known in the art and this mechanism is so arranged that only the movement of the gear in one direction will bring about the positive interlocking of the gear and the shaft whereby the wheel on the shaft will be driven, but the opposite movement of the gear is a free movement, having no positive effect upon the shaft. Such mechanisms are well known in the art and the installation of such a mechanism enables the operation of the de-

vice herein described to be carried out. Thus, on the downward movement of the segmental gear or rack 26, due to the downward movement of one end of the platform 16, the meshing of the teeth of the member 26, with the teeth of the gear 27, will bring about the downward driving of the shaft 28 and the wheel 10 and hence the scooter device. The upward movement of the member 10 permits, on the other hand, a free movement of the gear 27 and hence has no forward propelling action, but permits the member 26 to return again to its initial position freely without in any manner obstructing the propelling movement of the scooter device. Thus, by the mechanism described, it will be seen that any operator or user pressing upon the platform 16 in either downward or upward direction in respect to 20 the central part of the platform 16 will compress one spring and extend the other spring and bring about the downward movement of the gear member 26 so as to propel the scooter device forwardly; release of 25 pressure at one end of the platform permits the spring to bring the platform toward its initial position, the movement of the platform in this direction being limited by the buckle joint, and if such movement corresponds with the free movement of the 30 coaster brake, then the gear member 26 is enabled to be brought into its initial position preparatory to its propelling force.

Referring to Figure 3, I have shown a 35 form of coaster mechanism suitable for driving the wheels 10 from the gears 27. In this construction a ratchet wheel 30 may be secured to the wheel 10 and a pawl 31 to the gear 27. This pawl is urged inward into engagement with the ratchet 30 by means of a spring 32 having one end pivoted at 33 with the gear 27 and a stop 34 on the gear holds it in place. It will be observed that when the gear is turned in the direction of 40 the arrow, wheel 10 will be propelled forward, also that the wheel will be permitted to coast when the gear is stationary or turned in the reverse direction.

The device is very simple in its construction, very pleasing and agreeable in its use 50 on account of its resilient and yieldable characteristics and by virtue thereof and the combination of the propelling means, a scooter may be provided which will be readily operated by the users. It is the combination of the platform with the spring and buckle joints, that enables the propelling mechanism to propel a scooter device 55 of this kind and the combination of such parts is the subject matter of this invention. I have described an embodiment of my invention and various changes may be made 60 in the details of construction without departing from the spirit of the invention as defined in the appended claims.

I claim:

1. A scooter comprising in combination front and rear wheels with means for steering the front wheel and propelling means for the rear wheel, frame structures in which the said wheels are mounted, a platform between the wheels, pivot connections between said platform and said frames for connecting them, and a seat support carried by the rear wheel frame structure. 75

2. A scooter comprising in combination front and rear wheels with means for steering the front wheel, frame members in which said wheels are rotatably supported, seat supporting means carried by the rear frame member, a tilting platform pivotally connected with each of the frame members, coaster mechanism in the mounting of said rear wheel, and means on the tilting platform adapted to cooperate with said coaster 80 mechanism for propelling the scooter in a forward direction. 85

3. A scooter comprising in combination frame members in which front and rear wheels are supported, steering mechanism for the front wheel, propelling means for the rear wheel, a seat supporting member, a tilting platform having pivotal connections with the frame members, means for normally urging said platform upward from the frame members, and means on the rear end of the platform for operating the propelling means for the rear wheel. 90 95

4. A scooter comprising in combination, front and rear frame structures in which front and rear supporting wheels are mounted, steering mechanism for the front wheel, a driving coaster for the rear wheel including a driving gear, a seat supporting member on the rear frame, a platform for connecting the front and rear frame structures, a pivotal connection for the end of each frame with said platform, means for normally yieldingly urging said platform in an upward direction above the frame, and a gear rack carried by the rear end of said platform adapted to engage the driving gear on said driving coaster. 100 105 110

5. A scooter comprising in combination front and rear wheels with means for steering the front wheel and propelling means for the rear wheel, frame structures in which the said wheels are mounted, a platform between the wheels, pivot connections between said platform and said frames for connecting them, springs between said frames and said platform adapted to yieldingly press the platform upwardly with respect to said frame members, connections between the platform and said frame members for limiting said upward movement, and means on said platform for operating said propelling means. 115 120 125

6. In combination with a supporting body and a frame member pivoted thereto, a pair 130

of pivoted links angularly connected together and with said body and frame member, a stop on one of said links against which the other abuts for limiting the opening 5 movement of the links with respect to each other, and a spring for normally separating the ends of said links to normally hold them in the limited extended position.

7. A scooter comprising wheels, a frame, 10 a platform pivotally mounted on the frame, springs interposed between the platform and frame, in front of and to the rear of the pivotal connection therewith, and means connecting the platform and one of the wheels 15 for propelling the same.

8. A scooter comprising wheels, a frame and a platform pivotally mounted on the frame, springs one at either side of the pivotal connection between the platform and frame, link members between the platform 20 and frame, one set at either side of the pivotal connection, means limiting the movement of the link members, a mechanism for propelling one of the wheels, and means connected with said mechanism and with the 25 platform, for operating the mechanism on the pivotal movement of the platform.

In testimony that I claim the foregoing as my invention, I have signed my name hereto.

JOHN ROHDIEK.
